STOP MOTION FOR TEXTILE MACHINES

Philip N. Smith, Clemson, S. C., assignor to Deering Milliken Research Trust, Pendleton, S. C., a nonprofit trust of Maine

Application December 5, 1950, Serial No. 199,314

6 Claims. (Cl. 28—51)

1

The present invention relates to a novel automatic stop-motion device for use in the textile industry and, more particularly, to an improved device for arresting progress of all threads in a textile machine upon the occurrence of relaxation or loss of tension in any thread and for providing a selective indication of such relaxation.

The stop motion device of the present invention, while of general application, is particularly adapted for use with a textile warper and will therefore be described with reference thereto.

An electronic warper stop motion which is now in commercial use and which has been found to give satisfaction in operation is one in which ungrounded drop wires associated with threads coming from one side of a creel are connected through a resistor to the control grid of a normally energized electronic tube to cause deenergization of the tube upon grounding of a drop wire resulting from breakage of an associated thread, deenergization of the tube causing a relay to open the circuit of the motor advancing the thread and causing a signal lamp to be lighted. Similarly, in the above mentioned device, the ungrounded drop wires associated with the threads coming from the other side of the creel are connected through a resistor to the control grid of a second normally energized electronic tube to cause deenergization of the tube upon grounding of a drop wire and opening of the circuit of the motor and lighting of a signal lamp, an interlocking circuit being provided to prevent the closure of the circuit of one lamp after that of the other has been completed.

The above broadly described stop motion, as originally designed, required a relatively large number of components, some of which had to operate close to their rated tolerances. It was also relatively expensive to manufacture. A more recent version of such stop motion is a decided improvement over the original device in that fewer elements are utilized and the components thereof can operate well within their rated tolerances. This later version, however, has the drawback that the relays thereof tend to chatter when ends in different sections of the creel come down in rapid succession, that is, when the second end comes down before the relay responsive to the coming down of the first end has had time to release. The improved circuit of the present invention, while retaining all of the advantages of the simplified circuit of the above mentioned later stop-motion device overcomes this tendency of the relays to chatter and thus insures positive operation of the device irrespective of the

length of time between successive coming down of ends.

The single figure of the drawing illustrates a schematic perspective view of the essential elements of a stop-motion device for use in association with a warper and includes a circuit diagram of the new electrical circuit of the invention.

In the drawing, a warper creel is indicated diagrammatically at 1 as composed of vertical bars 2, each carrying a plurality of cones of thread 3. The threads are drawn through a comb 4 to a warp beam 5, which is rotated by a motor M. The improved device of this invention provides two terminal bars 7 and 8, which are respectively associated with the left side and right side of the creel, said bars being positioned transversely of the direction of travel of the threads. Each terminal bar has a multiplicity of drop wires 9 radially displaceable with respect to the bar and electrically connected thereto. These drop wires are upwardly bent, and each has a small aperture or eye 10 at the end remote from the connection to the terminal bar, said eye being adapted for passage therethrough of a thread. A metal contact bar 11 is positioned below and substantially parallel to the two terminal bars and at a distance therefrom such that the drop wires 9 make contact therewith when released by relaxation of the threads passing through the eyes 10 of these wires. The contact bar 11 is connected to a common ground circuit 12, and the terminal bars 7 and 8 are supported in suitable mountings (not shown) to insulate them from grounded elements of the machine.

The control circuit which is operated by the making of a contact between a drop wire 9 and ground bar 11 is made up of two similar networks one containing an electronic tube V responsive to such contact between the ground bar and a drop wire attached to the left-hand terminal bar 7 and associated with the left-hand section of the creel 1, and the other containing an electronic tube V' which is similarly responsive to closure of the circuit between the right-hand terminal bar 8 and the ground bar 11. The left-hand terminal bar 7 is connected through a current limiting resistor 13 to the control grid 14 of tube V. Control grid 14 is also connected to ground wire 12 through resistors 15, 17 and 22. The cathode 18 of tube V is connected directly to line 16. The plate 19 of tube V is connected through the energizing winding of relay R to a source of high potential comprising the rectified and filtered output from the secondary winding 20 of

a step-up transformer 21. One end of winding 20 is connected to ground wire 12 and the other end is connected to the anode of a diode rectifier 23, the cathode of which is connected through relay R to the anode of tube V and through relay R' to the anode of tube V'. A separate winding 24 of transformer 21 serves for energization of the cathode of diode 23. One electrode of a condenser 25 is connected to the cathode of rectifier 23 and the other electrode is connected to the junction of resistors 17 and 22. The primary winding 26 of transformer 21 is connected through suitable fuses f and a switch S to alternating current supply lines 21. A winding 28 on transformer 21 is provided to supply current to the cathode heaters of tubes V and V' through conductors xx (not shown). A pilot lamp P is connected across the winding 28 to signify when power is on.

The connection from the right-hand terminal bar 8 of the warper to the tube V' and the circuit connections of this tube are substantially identical to those of tube V. In the drawing, each element of the circuit of tube V' corresponding to a similar element in the circuit of tube V is indicated by the same reference character but with a prime (') added thereto.

Relay R has two armatures 29 and 30, the former of which over a back contact controls an alternative circuit for relay R' and the latter of which over a back contact controls the circuit for a signal light Lt and over a front contact controls the circuit of a motor controlling relay R-M. Similarly, relay R' has two armatures 29' and 30' controlling, respectively, an alternative circuit for relay R and the circuits of a signal lamp Rt and of the relay R-M. The alternative circuit for relay R comprises a lead 31 connecting the anode 19 of tube V with armature 29' of relay R' and a resistor 32, one end of which is connected to the back contacts 33 and 33' associated respectively with armatures 29 and 29' and the other end of which is connected to lead 16. The alternative circuit for relay R' comprises a lead 31' connecting the anode 19' of tube V' with armature 29 and resistor 32.

The circuit for signal lamp Rt may be traced as follows: from one power line 27 through switch S and a fuse f, through leads 34, 35 and 36 to lamp Rt, from lamp Rt through a lead 37' to back contact 38' of armature 30', armature 30', a lead 39 to a front contact 40 of armature 30, armature 30 and a lead 41 back to the other power line 27 through a fuse f and switch S. The circuit of signal lamp Lt comprises leads 34, 35 and 36, the lamp Lt, lead 37, back contact 38 of armature 30, armature 30 and lead 41. A resistor 42 has one end connected to the high potential end of relays R and R' and its other end connected to line 16, a condenser 43 being connected across the resistor 42.

The energizing coil of motor control relay R-M is connected across lead 34 and front contact 40' of armature 30'. It will be understood that commercial warpers use various different electrical systems to control the drive beam. Safety circuits to prevent overheating or the like, and "stop," "start" and "jog" switches are ordinarily provided. In order to indicate how the stop-motion device of the present invention can be readily coupled with such other circuits a relay Cr is indicated in the drawing as controlling a switch 44 in the lead 45 connecting the front contact 40' of armature 30' with relay R-M and a relay Cs is indicated as controlling a switch 46

in a line 47 bridging the contacts controlled by relays R and R'. Relay Cr is intended to symbolize any relay of such safety system that is normally energized during operation of the warper and relay Cs one that is normally deenergized but is adapted to be energized during closure of "start" and "jog" switches. The motor M for driving the warp beam is connected across suitable supply lines 48 through the armature 49 of relay R-M and a front contact 50 associated therewith.

With the circuit arrangement just described, when switch S is closed, power is supplied to the cathode heaters of tubes V and V' from winding 28. At the same time the cathode of rectifier 23 is heated from winding 24 causing the rectifier to pass current on alternate half cycles of the impressed voltage wave. Operating potential is then impressed through the windings of relays 20 R and R', respectively, upon the plates of tubes V and V'. Until the warp beam is started the threads from the creel will be slack and consequently the control grids of tubes V and V' will be grounded through the drop wires 9 and ground bar 11, biasing the tubes to cut-off. The current flowing through resistor 42 provides a potential difference across resistors 17 and 22 sufficient to maintain line 16, and therefore also the cathodes of tubes V and V' at above ground potential. Relay R or relay R', depending upon which has the quicker response, will become energized over its alternate circuit including back contacts of the other relay and, once energized will hold open the alternate circuit of the other relay. When, however, the beam is started by closure of the starting circuit including switch 46, the threads are brought under tension and the drop wires moved out of contact with the ground bar 11. Tubes V and V' will thereupon both pass current and both relays R and R' will be energized and their armatures will complete the holding circuit for the motor controlling relay R-M which thus is maintained energized after opening of the starting circuit.

If now a thread breaks, for example, one coming from the left side of the creel, the associated drop wire 9 drops and makes contact with ground bar 11, grounding bar 7 and bringing the potential of grid 14 of tube V below that of the cathode 18. Tube V therefore becomes deenergized, deenergizing relay R. Relay R thereupon drops its armatures, closing the circuit of lamp Lt over the back contact of armature 30 and opening the circuit of relay R-M at the front contact of armature 30. The resulting deenergization of relay R-M opens the circuit of the beam motor M at contact 50. When the beam stops rotating, all threads are slackened and hence the control grid of tube V' will be grounded and that tube will also cease passing current. Relay R' will not, however, become deenergized as its alternative circuit through resistor 32 to lead 16 was closed at the back contact 33 of armature 29 when relay 30 became deenergized. Lamp Rt will not be lighted as its circuit will remain open at the back contact of armature 30'. Thus, upon stoppage of the warp beam due to a broken thread, the operator can tell by the lighting of lamp Lt that the broken thread is on the left side of the creel. Similarly when relay R-M is deenergized as a result of a thread break on the right side of the creel relay R' is deenergized upon deenergization of tube V', relay R is maintained energized over its alternative circuit including the back contact of armature 29', the

circuit of lamp R_t is completed over the back contact of armature 30' and that of relay R—M is opened at the front contact of armature 30'. The lamp L_t will not light as its circuit is open at the back contact of armature 30. Should an end in the right side of the creel, for example, come down after one has come down on the left side of the creel but before the back contacts of relay R have closed, tube V' will also become deenergized but because of the potential drop across resistors 17 and 22 the potential of the cathodes will be held positive and the tubes will remain deenergized, thus insuring closure of the back contacts of relay R and energizing current for relay R'. It is the provision of resistor 42 in the circuit which insures that the cathodes of tubes V and V' will remain at positive potential at all times and thus prevents reenergization of a tube while an end associated therewith is still down. In the absence of resistor 42 when both tubes are deenergized prior to closure of the alternate circuit of either relay no current flows through resistors 17 and 22 and hence the cathodes of the tubes are grounded and momentary reenergization of one or the other of the tubes occurs and chattering of the relays results.

From the foregoing description of one specific embodiment of the invention, it will be apparent that the new stop-motion insures stopping of the warp beam upon breakage or slackness of a thread and provides a signal indicative of the location of the thread break which continues after all threads are slackened as a result of beam stoppage. The new circuit requires but few components, it is easy to install and to service and does not interfere with the operation of other safety circuits that may be in use with the particular warper to be controlled.

By way of illustration, but not of limitation, the circuit constants will now be given of one specific circuit which has been found particularly satisfactory with high speed warpers now in commercial use. In such circuit, tubes V and V' were halves of a double triode, a 6SN7, diode 22 was a 5Y3, resistors 13 and 13' were each 2 meg-ohms, resistors 15 and 15' were each .47 megohm, resistors 17 and 22 were each 5 kilohms, resistor 32 was 4.7 kilohms, lines 27 were 110 volt, 60 cycle power lines, and condensers 25 and 43 each had a capacity of 1 microfarad. The voltages of windings 24 and 28 were 5 volts and 6 volts, respectively, and that of secondary 20 was 700 volts.

The invention has now been described with reference to one specific embodiment thereof. Obviously, various changes in the particular circuit illustrated and described could be made without departing from the spirit of the invention or the scope of the accompanying claims. For example, although the invention has been described with reference to the preferred embodiment of the invention wherein indications are given of a yarn break in but two divisions of the creel, either the right side or the left side, the system can be readily expanded to indicate a yarn break in more than two divisions as will be readily apparent to those skilled in the art. If indications of a yarn break in a third division, for example in the center of the creel, are desired, it is only necessary to provide a third circuit, comprising a series connected relay and tube connected across the power supply with the control grid of the tube connected through a resistor with drop wires associated with the threads of such third division and to provide a third indicator lamp controlled by such third relay. The motor control relay

circuit would then be controlled over back contacts of the other relays as in the illustrated embodiment of the invention.

Furthermore, although the bars supporting the drop wires have been described as normally insulated from the ground, these bars could be grounded by connection to the ground wire of the circuit, in which case the contact bar would be divided into sections corresponding to the different parts of the creel and these sections connected respectively to the current limiting resistors in the grid circuits of the tubes. These and other variations and modifications are believed to be within the scope of the invention as described in the specifications and defined in the appended claims.

The following is claimed:

1. In a textile machine the combination comprising means for advancing a plurality of threads under tension, a guide means associated with each thread adapted to be moved when its associated thread is slackened, a pair of contacts associated with each guide means, means grounding one only of each pair of contacts, a pair of electronic tubes each having a cathode, a control grid and an anode, a resistor connected at one end to the control grid of one of said tubes and at its other end to the ungrounded one of certain of said pairs of contacts, a resistor connected at one end to the control grid of the other of said tubes and at its other end to the ungrounded one of certain other of said pairs of contacts, a source of energy, a pair of relays, the anode of each tube being connected to the high potential end of said source through one of said relays, grid leak resistors for said tubes, a common cathode resistor connecting the cathodes of said tube with the low potential end of said source, said low potential end of said source being grounded, whereby said tubes and relays are all energized when the threads are under tension but upon slackness of any one of the threads and consequent grounding of the control grid connected to the contact of the pair of contacts associated with the guide means for such thread the tube controlled thereby is deenergized and breaks the circuit of the relay connected thereto, means responsive to release of either relay for stopping said first mentioned means, means operative upon release of either relay to maintain the other relay energized, and means for maintaining a potential difference across said cathode resistor independently of the state of energization or deenergization of said tubes.
2. The combination according to claim 1 wherein said last mentioned means comprises a resistor connected at one end to the high potential end of said source and at its other end to the cathodes of said tubes.
3. In a warper stop motion device of the type wherein the control grid of a normally energized tube having also a cathode and anode is grounded through a wire when a thread breaks and deenergization of the tube releases a relay in series therewith across a source of energy the low potential end of which is grounded, the relay when released initiating stoppage of the warper, the improvement comprising a cathode resistor connected between the cathode of the tube and the low potential end of said source and means independent of the energization of said tube for maintaining a potential difference across said cathode resistor to prevent reenergization of the

tube while the control grid is grounded through a drop wire.

4. The combination according to claim 3 wherein said last mentioned means comprises a resistor connected in shunt with said relay and tube.

5. In a stop motion circuit of the type wherein a plurality of normally energized electronic tubes each having an anode, a control grid and a cathode, have their control grids connected to different groups of drop wires of a textile thread advancing machine, their anodes connected through different relay windings to the high potential end of a source of energy and their cathodes connected to the grounded low potential end of the source through a common cathode resistor and wherein release of a relay resulting from the grounding through a drop wire of the control grid of the tube in series with such relay initiates stopping of the thread ad-

vancing means of the textile machine and closes an alternate circuit for another relay, the improvement comprising means for maintaining a potential difference across said cathode resistor when all of said tubes are deenergized and thereby preventing momentary reenergization of a tube the grid of which is grounded through a drop wire.

6. The combination according to claim 5 10 wherein said last mentioned means comprises a resistor connected in series with said cathode resistor across the source of energy.
